UNITED STATES PATENT OFFICE.

GUSTAF E. WALLIN, OF POCATELLO, IDAHO, ASSIGNOR TO THE WALLIN ADDRESSING MACHINE MANUFACTURING COMPANY, OF KANSAS CITY, MISSOURI, A CORPORATION OF ARIZONA TERRITORY.

LINOTYPE-SLUG RECEIVER.

No. 873,642.

Specification of Letters Patent.

Patented Dec. 10, 1907.

Application filed March 26, 1907. Serial No. 364,668.

To all whom it may concern:

Be it known that I, GUSTAF E. WALLIN, a citizen of the United States, residing at Pocatello, in the county of Bannock and State of Idaho, have invented new and useful Improvements in Linotype-Slug Receivers, of which the following is a specification.

This invention relates to an improved slug receiver adapted to be used in connection with a linotype machine; and one of the objects of the invention is to provide a simple, convenient and efficient device for the purpose of receiving the slugs as they are cast and ejected from the machine, and for placing them in a galley, in such a manner as to be plainly visible to the operator, thus avoiding the necessity of handling the hot slugs, as is now frequently the case, for the purpose of making sure of the last word or matter set in a certain line, or in order to ascertain if the justifications are correct.

Further objects of the invention are to simplify and improve the construction and operation of this class of devices.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawings, Figure 1 is a side view of the slug receiving chute and related parts. Fig. 2 is a side view of the same as seen from the opposite side. Fig. 3 is a front view of the slug receiving chute and the galley support. Fig. 4 is a transverse sectional view taken on the plane indicated by the line 4—4 in Fig. 1. Fig. 5 is a perspective detail view showing one end of the operating lever. Fig. 6 is a sectional elevation of the upper portion of the slug chute with the near guide flange removed.

Corresponding parts in the several figures are denoted by like characters of reference.

The slug chute includes a base or bottom

member 1, which is adapted to be securely connected with the frame of a linotype machine, not shown, in a suitable position adjacent to the slot through which the slug is ejected. Said bottom member consists of a plate or bar, bent at an obtuse angle and including the approximately horizontal head piece 2 which is transversely apertured as shown at 3 for the passage of fastening members whereby it is to be mounted in position. In the upper side of the bottom member, at the angle between the head piece 2 and the inclined portion 4 is journaled a guide roller 5, said guide roller being accommodated in a recess 6 so that the said roller will project but slightly above the upper surface of the bottom member.

Secured upon the sides of the inclined portion 4 of the bottom member, adjacent to the upper end of said inclined portion, are guide flanges 7 and 8, provided at their upper ends adjacent to the receiving end of the chute, with upward extensions forming vertically disposed brackets 7'—8' one of which is provided with a slot 9 wherein a set screw 10 is vertically adjustable; said set screw carrying a pivoted lug 11 which is disposed between the brackets 7' and 8' in the path of the slugs that are being ejected from the machine, said lug being provided with a covering of leather or other suitable material as shown at 12, in order to avoid injury to the faces of the slugs. The pivoted or gravitating lug 11 is so adjusted as to lie in the path of the upper end of the slug, and it serves, as the slug passes over the guide roller 5, to tilt the slug backward, as indicated in dotted lines in Fig. 6, so that the slug will fall face upward and slide in this position over the inclined upper face of the bottom member 4 of the chute.

The inclined portion 4 of the bottom member 1 is provided with laterally extending pins 13 supporting a slidable plate or member 14 which is forced outward from the bottom member 1 by means of suitably arranged springs one of which is shown at 15 in Fig. 4, coiled upon the pin 13; the member 14 has an outward extending flange 16 which normally lies in alinement with and constitutes an extension of the guide flange 8, said flange 16 being disposed adjacent to the upper face of the inclined portion of the bottom member 1 so that it may slide laterally across said bottom member as indicated in dotted lines

in Fig. 4. The plate or member 14 has a laterally extending arm 17 provided with a slot 18 through which extends the handle portion 19 of a lever which is fulcrumed at 20 upon the side of the bottom member 1. The lever member 19 is connected through its fulcrum pin 21 with a crank arm 22, plainly seen in Fig. 5.

Pivotedly mounted at 23 upon the side of the bottom member 1 opposite to the lever 19 is an arm 24 carrying a thin rule or flange member 25 which normally extends upward adjacent to the side of the bottom member to constitute an extension of the guide flange 7. The arm 23 has a downward extending crank 26 which lies adjacent to and in the path of the crank 22 connected with the lever 19, and a spring 27 connects the arm 26 with the underside of the bottom member 1 so as to hold the arm 24 and flange 25 normally in the position indicated in full lines in Fig. 2, further movement in an upward direction of the arm 24 and related parts being obstructed by a pin or stop member 28.

25 A galley support is provided, comprising a suitable frame 29 which is supported adjacent to the slug receiving chute, and which is provided with adjustable holding members 30 and clamping members 31 whereby a galley of the desired dimensions may be supported in slug receiving position adjacent to the chute.

The lever 19 may be mechanically operated by means of an arm or bar 32 which is connected with a bracket 33 adapted to be pivotally supported in such a position as to enable one end of the arm 32 to be suitably connected with a live or moving part of the linotype machine with which the slug receiver is connected in such a manner as to be operated at the proper times to actuate the lever 19 which latter is disposed in the path of the upper arm 32 so as to be subject to lateral pressure from the latter. The precise manner of connecting the parts with the linotype machine may be varied within the scope of the invention.

The operation and advantages of this invention will be readily understood from the foregoing description taken in connection with the drawings hereto annexed, by those skilled in the art to which it appertains. As the slug which is shown at 35 is ejected from the machine it passes over the guide roller 5 beneath the gravity lug 11, which latter is adjustable to slugs of varying lengths, and it is tilted by contact with said lug so as to slide, face uppermost, in a downward direction over the inclined portion 4 of the bottom member 1 which constitutes the bottom of the chute until it is arrested by an upward portion or stop member 36 at the lower end of the chute. When the lever 19 is actuated, either mechanically or by the hand of the operator, it moves laterally

through the slot 18 of the arm 17, and the crank 22 connected with said lever will engage the crank 26 of the arm 24, thus tilting the latter against the tension of the spring 27 until the rule or flange 25 is depressed to the position shown in dotted lines in Fig. 2. Continued movement of the lever 19 will operate to force the plate 14 laterally against the tension of the springs 15, thus pushing the slug, by means of the upstanding flange 75 16, from the bottom member of the chute, over the depressed rule 25, and into a galley, not shown, which is supported in receiving position upon the frame 29 adjacent to the chute. The springs 15 and 27 serve to restore the box to normal or initial position when pressure upon the lever 19 is relaxed.

By this device, the slugs, as they are delivered or ejected from the machine, will be properly delivered into the galley in a position where their faces will be plainly visible to the operator. As the slugs accumulate in the galley, they may be removed by an attendant.

It is obvious that each operation of the lever 19 will cause the slugs contained in the galley to be displaced longitudinally in the galley to make room for the last slug; it is also evident that any portion of the slugs contained in the galley may be removed at any time without disturbing the remainder.

Having thus fully described the invention, what I claim as new is:

1. In a slug receiving attachment for linotype machines, an inclined chute having 100 guide flanges at the sides thereof, said guide flanges being provided with upward extending terminal brackets adjacent to the receiving end of the chute, and a slug tilting lug pivoted between said brackets. 105

2. In a slug receiving attachment for linotype machines, a receiving chute comprising a bottom plate or bar bent at an obtuse angle to present an inclined portion and an approximately horizontal portion, guide flanges adjacent to said plate or bar provided at their upper ends with terminal extensions at approximately right angles to the horizontal portion of the bottom plate, and a slug tilting lug pivotally supported and vertically adjusted between said upward extensions. 110

3. In a slug receiving attachment for linotype machines, a receiving chute comprising a bottom plate or bar bent at an obtuse angle to present an inclined portion and an approximately horizontal portion, guide flanges adjacent to said plate having upward extending terminal brackets at their upper ends disposed approximately at right angles to the horizontal portion of the bottom plate, a 120 slug tilting lug supported pivotally and vertically adjustable between said brackets, and a guide roller supported at the angle of the bottom plate, adjacent to said brackets. 125

4. In a slug receiving attachment for lino- 130

type machines, a slug receiving chute having guide flanges provided with spaced terminal brackets adjacent to the receiving end of the chute, a guide roller supported in the receiving end of the chute adjacent to said brackets in the path of slugs emerging from the machines, and a pivoted slug tilting lug supported for vertical adjustment between the brackets and having a covering strip of relatively soft material to engage the faces of the slugs for the purpose of tilting the latter.

5. In a device of the class described, a chute having guide flanges provided with upwardly extended vertical portions, a guide roller disposed in the bottom of the chute adjacent to said flanges, and a slug tilting lug supported between the flanges.

6. In a device of the class described, a chute having guide flanges provided with upwardly extended vertical portions, a roller disposed in the bottom of the chute adjacent to the flanges, and a slug tilting member supported for vertical adjustment intermediate the vertical portions of the flanges.

25. 7. In a device of the class described, a chute comprising a bottom member, stationary flanges at the upper end of said bottom member, a laterally movable flange at one side of the bottom member, and a vertically movable flange at the other side of the bottom member.

8. In a device of the class described, a chute comprising a bottom member, a laterally movable flange at one side and a vertically movable flange at the other side of the bottom member, in combination with means for successively moving the vertically movable flange in a downward direction and the laterally movable flange in a lateral direction 40 across the face of the bottom member.

9. In a device of the class described, a chute comprising a bottom member, a later-

ally movable plate having an upstanding flange, and a pivoted arm having an upstanding flange and a crank member, springs 45 for sustaining the movable plate and the pivoted arm in normal positions, and means for actuating said plate and arm against the tension of the springs.

10. In a device of the class described, a chute comprising a bottom member, a laterally movable spring actuated plate having an upstanding flange, and a pivoted arm having an upstanding flange and a spring actuated crank member, in combination with a lever 55 engaging the laterally movable plate to operate the latter against the tension of its actuating spring, said lever having a crank engaging the crank of the pivoted arm.

11. A slug receiving chute having at one 60 side a laterally movable flange adapted to move across the face of the bottom member of the chute and at the other side a vertically movable flange adapted to move to a disappearing position adjacent to the bottom 65 member of the chute, in combination with springs for sustaining said flanges in normal or initial position, and means for actuating said flanges against the tension of the springs.

12. In a slug receiving attachment for 70 linotype machines, a slug receiving chute having an inclined portion, a laterally movable flange at one side and a vertically movable flange at the other side of said inclined portion, stationary guide flanges at the upper end of the chute, and means for actuating the movable flanges.

In testimony whereof, I affix my signature in presence of two witnesses.
